UNITED STATES PATENT OFFICE.

HARRY B. WHEELER, OF CHICAGO, ILLINOIS.

SOUND-INSULATING DEVICE FOR BUILDING CONSTRUCTIONS.

1,342,610.

Specification of Letters Patent.

Patented June 8, 1920.

Application filed December 22, 1916. Serial No. 138,323.

To all whom it may concern:

Be it known that I, HARRY B. WHEELER, a citizen of the United States, residing at Chicago, in the county of Cook and State of Illinois, have invented a certain new and useful Improvement in Sound-Insulating Devices for Building Constructions, of which the following is a full, clear, concise, and exact description, reference being had 10 to the accompanying drawings, forming a part of this specification.

My invention relates to improvements in sound insulating devices for floor and wall constructions for buildings and has for its 15 object the provision of improved means for insulating the floor or wall to provide a sound proof construction so that the sounds on one floor of the building will not be transmitted to the floor above or below, and so 20 that the sounds in one room will not be transmitted to the adjacent rooms.

With these objects in view I provide a metallic plate arranged to be secured to the rough flooring in floor constructions and to 25 studding in wall constructions. This metallic plate is bent at its outer end so as to extend around the upper surface of a nailing strip to hold the nailing strip against movement away from the studding or rough 30 flooring. To insulate the nailing strip from the metallic plate I interpose between the plate and the strip a layer of insulating material such as felt.

These and other objects of my invention 35 will be more clearly brought out in connection with the accompanying drawings wherein:

Figure 1 is a cross sectional view of the preferred form of my invention showing it 40 applied to floor constructions;

Fig. 2 is a plan view thereof;

Fig. 3 is a modified form wherein the metallic holder is made up of one piece of material;

Fig. 4 is a view of a holder used in connection with wall constructions and attached to the studding of a building;

Figs. 5, 6, and 7 are modifications of the nailing strip holder;

Fig. 8 is a cross sectional view of a holder embedded in concrete;

Fig. 9 is a cross sectional view of a modified form of holder which does not extend around the underside of the nailing strip; 55 and

Fig. 10 is a perspective view of a nailing strip and two holders or retaining devices as shown in Fig. 1 holding the strip in place.

Similar characters of reference refer to similar parts throughout the several views.

Referring first to Figs. 1 and 2, 11 illustrates the support or rough flooring to which is attached by means of the nails 12—12, or any other suitable means, the holder or clamping device 13. In the preferred form 65 of my invention this clamping device consists of two pieces 14 and 15 riveted together, as shown at 16, the member 15 constituting the base member which is attached to the support 11, as referred to. The member 14 70 normally extends upwardly, as shown by the dotted lines. The nailing strip is shown at 17 and is provided with a notch 18 having a beveled surface 19. A layer of insulating material, such as felt, is interposed between 75 the clamping device and the nailing strip as illustrated at 20 and the lower end of the layer is clamped between the upturned end 21 of the base member 15 and is held in such position by means of the nails 12—12 which 80 extend through the insulating material. After the clamping device has been secured to the rough flooring and the nailing strip, together with the insulating layer 20, assembled, the upper end of the clamping device 85 13 is forced downwardly to the position illustrated in full lines. This is accomplished by means of a hammer or hatchet and serves to hold the nailing strip against movement away from the rough flooring or 90 support 11. The flooring 22 is then nailed to the strip 17 as indicated. To insure against any possible connection between the clamping device and the flooring 22 the felt layer 20 may be extended at its upper end 95 around the upper end of the clamping device to entirely separate the clamping device from the upper flooring. The clamping devices 13 are spaced approximately two feet apart and are positioned alternately on 100 opposite sides of the nailing strip, as most clearly shown in Fig. 10.

In Fig. 3 the clamping device 13^a is constructed of one piece and has its underside stamped upwardly as shown at 23 so as to 105 space the nailing strip away from the rough flooring or support 11^a. In this construction the upwardly extending part of the clamp 13^a is stamped out of the piece 24 which is nailed to the support.

Fig. 4 shows the clamping device applied to wall constructions and has its base plate 15^b bent to form an inwardly projecting piece 25 which is nailed, as shown, to the 5 studding 26. The wall 27 is secured to the nail strip 17^b as is the upper flooring shown in Fig. 1.

Fig. 5 shows a floor construction similar to that of Fig. 1 except that the member 14^c 10 includes an upwardly extending piece 28 arranged to engage that side of the nail strip opposite the clamping portion of the retainer.

Fig. 6 shows a floor construction wherein 15 the nail strips 17^a are supplied with beveled surfaces 29 and 30 which extend the full length of the strip if desired. In this case the layer of felt 20^a is inserted, as shown, and the upper portion 14^a forced 20 from the position shown in dotted lines to the position shown in full lines to hold the nail strip in place. The several clamping devices are placed alternately on opposite sides of the nail strip.

25 In Fig. 7 the clamping devices 14^e are constructed with their upper ends 31 bent inwardly to extend over the beveled surface of the notch 18^e formed in the nail strip 17^e, thus avoiding the necessity of bending 30 the clamping devices to the extent necessary in the other devices shown.

Fig. 8 shows a clamping device embedded in concrete. In this construction the clamping device consists of the two members 14^g 35 and 15^g. The member 15^g constitutes the base member and is bent upon itself, as indicated, to provide at its right hand end (Fig. 8) a clamp for holding the lower end of the felt strip 20^g. The member 14^g extends through the slots 32 in the base 15^g and has its lower end bent, as shown at 33, and provided with an aperture 34 to permit nailing of the piece 14^g to the support 35. The member 14^g is first nailed to 45 the support 35 and the concrete poured around the member 14^g. After the concrete becomes hard the member 15^g is placed over the clamp 14^g and the felt layer 20 positioned between the right hand ends of the 50 member 15^g. The nail strip 17^g is then notched and placed in position whereupon the upper end of the clamping device 14^g is hammered downwardly, as shown, to hold the nail strip in place. Due to the enlarged end 33 of the member 14^g the clamping 55 device is securely anchored in the concrete.

In Fig. 9 the clamping device 36 takes the form of an angle and is attached by means 60 of two nails 37 to the support 11^h. The felt layer 20^h is placed between the clamp 36 and the nail strip 17^h and between the nail strip and the support 11^h. The nail strip is notched, as shown, and the upper end of 65 the clamp 36 hammered down from the

dotted line position to the full line position to hold the strip in place. The several clamps 36 used on each nail strip are placed alternately on opposite sides of the strip, as are the devices shown in Fig. 10 so 70 that lateral displacement of the nail strip is prevented.

It will be seen from the above description that I provide means for insulating the nail strip from its support which is simple 75 in construction and can easily and quickly be applied to the nail strips. Due to the fact that the clamping device is bent by means of a hammer or other suitable tool the necessity of providing accurate beveled faces 80 on the nail strips is prevented since the clamping device may be forced to assume any shape which is required in order that it may securely hold the strip in place.

Having thus described my invention 85 what I claim as new and desire to secure by Letters Patent of the United States is:

1. In a building construction the provision of a support, a nail strip, a malleable metal nail strip holder secured to 90 the support and extending over the nail strip to prevent movement of the strip away from the support, and a layer of insulating material between the nail strip and the holder to insulate the strip from the support.

2. In a building construction the provision of a support, a nail strip provided with a notch in its side opposite the support, a malleable metal retaining device carried 100 by the support and having an upwardly extending part fitting into said notch, and sound insulating material between the retainer and the nail strip.

3. In a building construction the provision of a support, a nail strip provided with a notch in one of its edges opposite the support, a malleable metal retaining device carried by the support and having an upwardly extending part fitting into said 110 notch, and sound insulating material between the retaining device and the nail strip.

4. In a building construction the provision of a support, a nail strip, a plurality of strip retainers, each having an outwardly extending piece extending over the nail strip to prevent movement of the strip away from the support, said retainers being positioned along the strip so that 115 the outwardly extending pieces are alternately positioned on opposite sides of the nail strip, and sound insulating means between the retainers and the nail strip.

5. In a building construction the provision of a support, a nail strip insulated from the support, a malleable metal nail strip holder secured to the support and having its base interposed between the nail strip and the support, said holder having a 125 130

part extending outwardly from the support on one side of the nailing strip and over the strip to prevent movement of the strip away from the support, insulating material between the nailing strip and holder to insulate the strip from the support, and a clip formed on the base of the holder for securing the insulating material to the holder.

In witness whereof I hereunto subscribe my name this 18th day of December, A. D. 1916.

HARRY B. WHEELER.
